United States Patent Office

Des. 202,334

Patented Sept. 21, 1965

202,334

DOMESTIC DWELLING

Daniel Schwartzman, New York, N.Y., assignor to Gordon E. Sugar, Pikesville, Md.

Filed Mar. 9, 1965, Ser. No. 84,169

Term of patent 14 years

(Cl. D13—1)

FIG. 5

I claim:

The ornamental design for a domestic dwelling, substantially as shown and described.
